[57] **CLAIM**

The ornamental design for a piston for compressors employed in automobile air-conditioners, as shown and described.

DESCRIPTION

FIG. 1 is a front elevational view showing a piston for compressors employed in automobile air-conditioners according to a first embodiment of the present invention; FIG. 2 is a rear elevational view showing the piston of FIG. 1;

FIG. 3 is a top plan view showing the piston of FIG. 1; FIG. 4 is a bottom plan view showing the piston of FIG. 1; FIG. 5 is a right side elevational view showing the piston of FIG. 1, the left side view being a mirror image thereof; FIG. 6 is a cross-sectional view taken along line 6—6 of FIG. 1;

FIG. 7 is a cross-sectional view taken along line 7—7 of FIG. 5;

FIG. 8 is a cross-sectional view taken along line 8—8 of FIG. 5;

FIG. 9 is a perspective view showing the piston of FIG. 1; FIG. 10 is a front elevational view showing a piston for compressors employed in automobile air-conditioners according to a second embodiment of the present invention; FIG. 11 is a rear elevational view showing the piston of FIG. 10;

FIG. 12 is a top plan view showing the piston of FIG. 10; FIG. 13 is a bottom plan view showing the piston of FIG. 10; FIG. 14 is a right side elevational view showing the piston of FIG. 10, the left side view being a mirror image thereof; FIG. 15 is a cross-sectional view taken along line 15—15 of FIG. 10;

FIG. 16 is a cross-sectional view taken along line 16—16 of FIG. 14;

FIG. 17 is a cross-sectional view taken along line 17—17 of FIG. 14;

FIG. 18 is a perspective view showing the piston of FIG. 10; and,

FIG. 19 is a cross-sectional view showing a piston according to the present invention employed in a compressor.

The broken lines in FIG. 19 are shown for illustrative purposes only and form no part of the claimed design.
